EARTH CUTTING TOOL

Charles Clark Merrick, Greenville, Tex.

Application April 28, 1950, Serial No. 158,864

8 Claims. (Cl. 255—73)

1

This invention relates to new and useful improvements in earth cutting tools.

The invention is particularly concerned with a tool for forming a bore or opening extending horizontally through earth sections, such as under a railroad or highway, or in other locations where the cutting of an ordinary ditch is not feasible for the laying of pipe and other conductors. It is to be kept in mind, however, that the invention is not limited to the forming of horizontal openings or bores, since it is applicable with obvious modifications to other types of bores or openings.

It is one object of the invention to provide an improved earth cutting tool which is simple and effective in operation, and with which large openings beneath or through sections of earth may be formed with facility and speed.

A particular object of the invention is to provide an improved earth cutting tool which cuts and forms the earth as it passes therethrough, as contrasted to the type of tool which seeks to compress or to remove entirely a quantity of earth in one passage of a tool and hence encounters tremendous physical stresses and loads.

An important object of the invention is to provide an improved earth cutting tool which cuts the earth formation into a plurality of sections and at the same time applies pressure to said sections so as to compact the same and to cause the sections to adhere together as individual elements which may subsequently be forced from the bore which has been formed.

A further important object of the invention is to provide an improved cutting head for an earth cutting tool adapted to be moved longitudinally through an earth section and to cut or divide the section longitudinally into a plurality of ribbons which subsequently are severed from the earth formation and compressed or compacted into elongate coherent ribbons which are easily pushed or driven from the bore which is being formed.

A still further object of the invention is to provide a novel device for permitting selective reaming or enlarging of an opening which has previously been formed, and which permits such selective reaming to be in any portion of said opening.

A pertinent object of the invention is to provide an improved method of forming openings through earth sections where ordinary drilling operations are not feasible.

A construction designed to carry out the invention will be hereinafter described together with other features of the invention.

2

The invention will be more readily understood from a reading of the specification and by reference to the accompanying drawings, wherein examples of the invention are shown, and wherein:

Fig. 1 is a view in perspective of a cutter head for an earth cutting tool constructed in accordance with this invention and adapted to carry out the teachings of this method,

Fig. 2 is a cross-sectional view of the cutter head,

Fig. 3 is an enlarged, longitudinal, sectional view of the cutter head,

Fig. 4 is a cross-sectional view taken upon the line 4—4 of Fig. 3,

Fig. 5 is an enlarged sectional view showing the mounting of the reaming foot,

Figs. 6, 7, 8 and 9 are schematic views illustrating the various operations of the cutting tool and exemplifying the carrying out of this method, and

Fig. 10 is an enlarged view in perspective of the reaming foot.

In the drawings, the numeral 10 designates an earth section or formation through which it is desired to form a horizontal opening or bore. In this case, the illustrated earth section is a highway road bed, but it is noted that the invention is equally applicable to any other type of earth formation or section, and is not necessarily limited to an elevated section, such as that illustrated, since the lateral portions of the section may be exposed through the digging of ditches or pits, and need not be previously exposed to permit utilization of this invention.

Many types of devices are presently available in a commercial form for forcing pipe lengthwise, either away from the device or into the device, and such a mechanism is illustrated schematically at 11 in Figs. 6 through 9. In carrying out the first step of the bore forming operation, a suitable pipe or elongate conductor 12 is closed at one end by a cap 13, and is forced through the earth section 10 by means of the mechanism 11. Although any suitable type of cap may be used to close the end of the pipe 12, it has been found that a cap having a flat end is desirable since it is less easily deviated from its proper path. Indeed, the cap 13 could be omitted entirely and the pipe 12 allowed to fill with earth as it passes through the section 10. In general, this is not desirable, since the pipe would have to be cleaned out before it could be used again, or would have to be discarded and new pipe employed. Nevertheless, the important and only essential feature of the first step is the

forming of an opening A of relatively small diameter through the earth section 10.

After the pipe 12 has been forced entirely through the earth section 10 and is projecting from the opposite side thereof, the cap 13 is removed, and the earth cutter head 14, illustrated in Fig. 1, is connected to the projecting end of the pipe. The cutter head 14 includes an elongate central body 15 having provision for water courses to be described hereinafter and preferably being hollow. Ordinary metal pipe may conveniently constitute the body 15. The latter is threaded at each end for connection with the pipe 12 and for reception of a suitable cap 16. A plurality of cutter fins 17 extend radially from the exterior of the body 15, the fins being relatively elongate and substantially rectangular in shape, and being evenly spaced about the outer periphery of the body 15 as shown in Figs. 1 and 2. While the fins may be formed integrally with said body, they are preferably affixed thereto by welding or other suitable securing means and extend lengthwise or longitudinally of the body throughout a major portion of its length. As shown in Fig. 3, the fins 17 are wider at one end than at the other and taper lengthwise to a slight degree from their leading edges 18 to their trailing edges 19. The leading edge of each of the fins is bevelled or sharpened to form a cutting edge, and the outer edge of each of the fins is similarly bevelled or sharpened at 20, as illustrated in Fig. 2. A cutting band 21 encompasses the trailing edges of the fins, having one edge substantially aligned with the trailing edges 19 and being secured by welding or in any other suitable fashion upon the outer edges of the fins 17 so as to extend a short distance lengthwise of said fins. The band 21 is substantially wedge-shaped in cross-section having its rearward edge, which is positioned substantially flush or in alignment with the trailing edges 19 of the fins 17, relatively flat and blunt, while its cutting edge, disposed toward the cutting edges 18 from the trailing edges 19, is relatively sharp and thin. The outer surface 22 of the band is substantially cylindrical, and is disposed parallel to the axis of the body 15. The inner periphery 23, however, of the band forms a portion of a cone having its axis co-incident with the axis of the body 15, and hence the longitudinal thickening of the cutting ring which provides the wedge-shaped cross-section thereof, is substantially all toward the axis of the body 15. Hence the openings 24 which are defined between each pair of the fins 17 and encompassed by the band 21, decrease in cross-sectional area as one moves from the leading edge of the cutting band to the trailing edge thereof.

A plurality of relatively small radial openings 25 are cut in the body 15, one of the openings being provided between each pair of the fins 17 and being situated substantially intermediate the ends of said fins. Although, in the preferred form of the invention, the body 15 is formed of ordinary pipe and access is easily had from the pipe 12 through the bore of said pipe to the openings 15, it is pointed out that any suitable type or character of water-courses may be employed for conducting fluid under pressure from the pipe 12 to the openings 25.

Following the forcing or driving of the pipe 12 through the earth section, the cutter head 14 is secured to the projecting end of said pipe 12, and then the action of the mechanism 11 is reversed to force the cutting head back through the earth section. At the same time, a suitable fitting

26 is connected into the pipe 12 and a fluid under pressure, normally water, is introduced into the interior of the pipe 12 and hence into the interior of the body 15. As the head 14 is pulled through the earth formation, the leading edges 18 of the fins 17 penetrate the walls of the opening A formed in the first step of the method, and form radial slits or cuts in said walls. Further, as the fins continue their passage through the earth, and because of their lengthwise taper, said slits or cuts are deepened until the earth encounters the cutting ring 21. At this point, it is to be noted that the initial passage of the pipe 12 through the earth formation results in a compacting of the earth formation so that the walls of the opening A are substantially denser or more compressed than remote portions of the earth formation. This compacting action is continued by the passage of the fins 17 through the previously compacted earth, it being noted that the fins do not remove earth but merely push the same aside to permit their passage. The final compacting and the severing of the compacted earth from the surrounding formation is accomplished by the cutting ring 21 which severs from the surrounding earth formation the ribbons of earth partially formed by the passage of the fins 17. The severing occurs at the leading edge of the ring 21, and as the ribbons of earth pass rearwardly through the openings 24, they are additionally compressed by the converging walls of said openings and exit from the openings in the form of an elongate ribbon or rod of roughly rectangular cross-section and with a greatly increased density and coherence due to the compacting actions to which the dirt has been subjected. Thus, when the passage of the cutting head 14 through the opening A has been completed, the opening has been enlarged to form a bore of larger diameter, which will be designated by the letter B, and a plurality of ribbons or rods C of highly compacted and compressed earth are lying within said opening B.

Following this step, the cutting head 14 is removed from the pipe 12 and replaced by a substantially cylindrical head or ram 27 which is pushed through the opening B by means of the pipe 12 and forces the elongate ribbons C therefrom. Since the ribbons or rods C have been greatly compacted, they lend themselves readily to this operation and are simply extruded from the opposite end of the bore B.

It is to be noted that this cutting operation, and the concurrent supply of water under pressure through the openings 25, does not result in the forming of a slurry or mud mixture, since the openings 25 are small in diameter and since only a small quantity of water passes therethrough. The water functions simply as a lubricating agent and prevents the earth from sticking to the fins 17 and the cutting ring 21. The quantity of water is not sufficient to soften or loosen the earth, and it does not adversely affect the dense and compact nature of the earth ribbons or rods C.

In some cases, it may be desirable to enlarge the opening B, either upwardly or downwardly in order to permit the positioning of a pipe or other conductor within said opening with a desired degree of pitch or fall. In this case, it is desirable to use the cutting shoe 28 shown in Figs. 5 and 10, and which includes a shank 29 having a foot 30 directed at right angles therefrom. A short section of pipe or other support 70 31 is provided for carrying the shoe 28, and is

connected between the pipe 12 and the cutting head 14. The pipe 31 is provided with a pair of diametrically opposed transverse openings 32 within which the shank 29 is received, and a suitable set screw or bolt 33 is provided for holding the shoe in position within said openings. It is obvious that by means of a set screw, the shoe may be adjusted so as to project any desired distance laterally of the pipes 12 and 31, and since the shoe bears upon the inner surface or wall of the bore B, the cutter head 14 will be displaced a corresponding distance laterally with respect to the other side of said bore. When this assembly is passed through the bore, the cutting head will necessarily ream or cut additional quantities of earth from one side of the bore B, and said bore will be enlarged as desired.

It is further to be noted that openings of large diameter may sometimes be required, and that such openings may be too large to be cut by a single passage of the cutting head 14 due to the large quantities of power required to form such a large opening. In this case, it is desirable to provide the cutting head 14 in a number of variety of diameters, and to pass successively larger diameters of the cutting heads through the bore to enlarge the same to the desired diameter. In such case, it may be desirable to connect the head or ram 27 between the pipe 12 and the cutting head 14, so that said ram functions as a pilot and maintains the cutting head properly centered with respect to the bore being enlarged.

By means of the cutting structures herein set forth and the method herein disclosed, openings or bores are readily formed in earth locations without requiring the digging or cutting of a ditch through said formation, and lengths of pipe or other conductors may readily be passed through the bores so formed.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. An earth cutting tool including, an elongate central body, a plurality of radial cutters carried by the body, each radial cutter comprising an elongate plate having its inner longitudinal edge adjoining the central body, the plate extending radially outwardly from the body and having its outer longitudinal edge formed with a radially-outwardly facing cutting edge, and an annular cutter ring encircling the radial cutters at one end thereof, the outer longitudinal edges of the radial cutters adjoining the ring, and the ring being provided with an annular cutting edge facing longitudinally of the central body toward the cutting edges of the radial cutters.

2. An earth cutting tool including, an elongate central body, an annular cutter ring encircling the body and spaced therefrom, the ring having a circumferential cutting edge facing longitudinally of the central body, a plurality of radial cutters extending radially between the ring and the body so as to divide the space between the

ring and the body into a plurality of earth-receiving passages, each of the radial cutters comprising an elongate plate having its inner longitudinal edge adjoining the central body and a radially-outwardly facing cutting edge on its outer longitudinal edge, the radial cutting blades projecting from the ring and extending longitudinally of the body in the direction in which the ring cutting edge faces.

3. An earth cutting tool including, an elongate central body, a plurality of cutter blades extending radially outwardly from the body, each of the cutter blades comprising an elongate plate having one longitudinal edge adjoining the central body substantially throughout the length of said plate and having a radially-outwardly facing cutting edge on its outer longitudinal edge, and a relatively short cutter ring encircling the cutter blades and adjoining the outer longitudinal edges thereof, the cutter ring having a circumferential cutting edge facing longitudinally of the cutting tool, and the cutter blades extending from within the cutter ring in the direction in which the cutter ring cutting edge faces.

4. An earth cutting tool as set forth in claim 3, wherein the cutting edges of the cutter blades merge into the cutting edge of the ring.

5. An earth cutting tool as set forth in claim 3, wherein the portions of the blades extending from within the cutter ring are progressively decreased in width to incline the cutting edges of the blades progressively nearer the axis of the central body.

6. An earth cutting tool as set forth in claim 3, a central support alined with the central body and connected thereto, and a shoe having an earth-engaging face and carried by the support, said shoe being spaced laterally from the support to force the ring cutter to cut in a laterally-displaced path.

7. An earth cutting tool as set forth in claim 3, wherein the cutter ring is progressively increased in wall thickness from its cutting edge to its opposite edge.

8. An earth cutting tool as set forth in claim 3, wherein the cutter ring is progressively increased in wall thickness from its cutting edge to its opposite edge and the cutter blades terminate in the transverse plane of said opposite edge of the cutter ring.
